CLAIM

We claim the ornamental design for a heater, as shown and described.

DESCRIPTION

FIG. 1 is a front perspective view of a heater of the present invention.

FIG. 2 is a rear perspective view of a heater of the present invention.

FIG. 3 is a front elevation view of the heater of FIG. 1.

FIG. 4 is a rear elevation view of the heater of FIG. 1.

FIG. 5 is a side elevation view of the left side of the heater of FIG. 1.

FIG. 6 is a side elevation view of the right side of the heater of FIG. 1.

FIG. 7 is a top plan view of the heater of FIG. 1; and,

FIG. 8 is a bottom plan view of the heater of FIG. 1.

In the drawings, the broken lines depict portions of the heater that form no part of the claimed design.
